(57) **CLAIM**

The ornamental design for an insulating sleeve for an electrical meter as shown and described.

DESCRIPTION

FIG. 1 is a top, front, right side perspective view of an insulating sleeve for an electrical meter showing our new design.

FIG. 2 is a bottom, rear, left side perspective view thereof.

FIG. 3 is a right side elevation view thereof.

FIG. 4 is a front elevation view thereof.

FIG. 5 is a rear elevation view thereof.

FIG. 6 is a top plan view thereof.

FIG. 7 is a bottom plan view thereof.

FIG. 8 is a left side elevation view thereof.

FIG. 9 is a first cross-section view thereof taken along line **9-9** of FIG. 6; and,

FIG. 10 is a second cross-section view thereof taken along line **10-10** of FIG. 7.

The cross-section designation arrow lines **9-9** and **10-10** in FIGS. 6 and 7, respectively, form no part of the claimed design.

1 Claim, 10 Drawing Sheets
